UNITED STATES PATENT OFFICE.

EMIL DEISTER, OF FORT WAYNE, INDIANA, ASSIGNOR TO DEISTER MACHINE COMPANY,
OF FORT WAYNE, INDIANA, A CORPORATION OF INDIANA.

CONCENTRATING-TABLE.

1,209,943.

Specification of Letters Patent. Patented Dec. 26, 1916.

Application filed June 15, 1916. Serial No. 103,809.

To all whom it may concern:

Be it known that I, EMIL DEISTER, residing at Fort Wayne, in the county of Allen and State of Indiana, a citizen of the United States, have invented or discovered certain new and useful Improvements in Concentrating-Tables, of which improvement the following is a specification.

The invention described herein relates to 10 certain improvements in concentrating tables and has for its object a construction of table especially adapted for the treatment of ores in which a large percentage of the values occur in thin minute flakes. 15 Experience has shown that the flakes move over a table with their larger surfaces substantially parallel with the surface of the table and hence settle down very slowly through the gangue. Hence when the table 20 is constructed and riffles so arranged that the depth of the material being treated is comparatively deep on some portion of the table above the upper surfaces of the riffles, a large percentage of the flaky values will 25 not, in passing from one riffle to the next, settle down far enough to be positively caught by the riffles, and held from further movement toward the tailings discharge edge. It frequently occurs that flakes will 30 lodge against a riffle close to the upper edge of the latter, and the action of the flowing material will lift the flakes causing them to turn somer-saults over the riffle. In such turning movement the flakes will move upwardly through the gangue, and a considerable percentage will either not settle down sufficiently to be caught by the next 35 riffle, or settle only such a distance as to strike the upper edge of the next riffle and 40 somer-sault over it as before stated.

It has been the practice, to use tapering riffles on concentrating tables, say from three-eighths inch to five-eighths inch high on one end and having a feather edge on the 45 other end. This construction of riffle has a tendency to bank or thicken the pulp near the center of the table, and as the flaky mineral will not stratify or settle very well in a thick or deep pulp, it follows, that such 50 a construction of riffle is not desirable when treating flaky ores.

The invention described herein consists generally stated in a construction of table and riffles permitting of the maintenance 55 of a comparatively thin shallow bed or stream of material spread evenly above the

riffles over the entire surface of that portion of the table where gravity separation occurs, and the provision of means for producing a cleaner mineral and a more perfect control of the line of separation between the mineral and gangue. 60

The invention is hereinafter more fully described and claimed.

In the accompanying drawings forming a 65 part of this specification, Figure 1 is a top plan view of a concentrating table embodying the improvements claimed herein; Figs. 2 and 3 are sectional views on planes indicated respectively by the lines II—II, and 70 III—III Fig. 1 and Fig. 4 is a detail side view of the forward portion of a riffle, on an enlarged scale.

In the practice of the invention, the outline of table 1, in plan view, is not material. 75 The pulp is directed onto the feed side of the table through the feed box 2, and dressing water is supplied to the launder 8; the table being slightly inclined from the feed side toward the tailings discharge edge 3, the 80 pulp and dressing water will flow transversely of riffles 4, toward such edge. The inclination of the table from the feed side to the edge 3 and the spacing and height of the riffles are adapted to permit of the 85 settling of the values even when in the form of thin flakes, down through the gangue into the grooves formed by the riffles. The movement of the values toward the mineral discharge edge 5 is effected by 90 the differential vibrations of the table substantially parallel with the riffles as indicated by the arrows a. The mechanism employed for imparting differential vibrations of the table may be effected by any suitable 95 construction, such mechanism being diagrammatically indicated in the drawings.

As the values approach the mineral discharge end of the riffles, they are caused to move up and ahead of the overlying gangue 100 by the inclined surface 6 arranged transverse of the line of movement of the values caused by the vibration of the table. The inclined surface 6 is arranged diagonally across the table, and terminates in a raised 105 portion or plateau 7. The shape or contour and extent of the plateau beyond the inclined surface 6 is dependent largely on the general shape of the table and the area required for cleaning up. It has been found 110 that when treating lean ores, the values are discharged from portions of the plateau

adjacent to the lower end of the inclined approach to the plateau. In such cases only a comparatively narrow washing surface or plateau is required. The plateau preferably has its surface parallel or substantially parallel with the main or stratifying surface of the table. By reason of the slight retardation of the movement of the minerals due to the inclined surface 6, the minerals 10 will be crowded together to a certain extent at the foot of the incline and up along its surface, but as soon as they pass onto the plateau their rate of movement will be accelerated and the mass formation will be 15 destroyed and the particles will move in a thin layer over the surface of the plateau, thereby facilitating the final dressing of the mineral by the wash water directed onto the plateau by the launder 8.

20 As heretofore stated, the low efficiency of the tables now in use in treating ores containing values in the form of thin flakes, is due to the excessive depth of material above the riffles on some portions of the stratifying zone, and too thin a bed on other portions of the stratifying zone of the table. Heretofore it has been the practice to incline the table not only transversely of the riffles, but also parallel therewith, the mineral discharge 25 edge being higher than the opposite end of the table. This longitudinal inclination, in connection with riffles tapering throughout their length, tends to cause the material to bank up on some parts of the table and reduces the depth of the material, 30 too much so over other portions of the table, a condition unfavorable for the gravity separation of flaky minerals. In operating the improved table it is inclined in one direction 35 only *i.e.* from the head, or feed side toward the tailing discharge edge as indicated in Fig. 3 and maintained substantially level in the direction of the vibrations as indicated in Fig. 2. This position of the table 40 permits of the employment of riffles having their upper edges substantially the same height at all points above the main or gravity separating surface of the table, and in order that portions of the riffles extending 45 across the incline 6 may have their surface substantially in a level with other portions of the riffles, the latter have the portions on the incline 6 beveled off as shown in Fig. 4. The riffles and the plateau are so constructed 50 and proportioned that the surface of the latter will be a distance above a plane co-incident with the upper edges of the riffles approximately equal to the desired depth of material above such plane. This construction of riffles and adjustment of the table 55 permits of the maintenance of an approximately equal depth of material over all portions of the stratifying zone of the table. In operating the improved table the trans- 60 verse inclination toward the tailing dis-

charge edge is so adjusted that the level of pulp along the zone corresponding with the foot of the incline will be co-incident with or very slightly below the surface of the plateau, relative to the line of movement of 70 the table.

It is characteristic of the improved table that the visible line of separation between the mineral and gangue will be substantially along or adjacent to the juncture of the incline and plateau. 75

As indicated in the accompanying drawings, the riffles used on the improved table extend from the rear end of the table, and terminate in a diagonal line *i.e.* a line an 80 angle less than a right angle to the direction of vibration of the table, and are so constructed that their effective height above the stratifying surface of the table is maintained in the direction of the length thereof, 85 and extends to the foot of the incline 6, and from the foot of the incline 6 to the crest thereof the riffles are tapered or beveled abruptly, this beveled portion of the riffles corresponding approximately with the incline 90 6, and terminating at or adjacent to the crest of the incline.

I claim herein as my invention:

1. A transversely inclined concentrating-table having a deck, means for vibrating the deck, riffles arranged on the deck substantially parallel with the direction of vibration, means for feeding the material onto the head of the table, said table being downwardly inclined from the head to the tailings discharge edge, but substantially level in the direction of vibration, the riffles having their upper surfaces in a plane substantially parallel with the main surface of the deck for substantially their entire length, 100 in combination with a plateau, substantially parallel with the main surface of the table and arranged along the mineral discharge edge, and an inclined surface arranged diagonally across the deck for causing the values 105 to move up above the surface of the material overlying the main surface of the deck and onto the plateau.

2. The combination of a transversely inclined concentrating-table, with a plateau having an inclined approach and riffles arranged on said table, and extending only to the line of junction of the plateau and its inclined approach, the upper edges of the riffles and the surface of the plateau being substantially parallel, and the surface of the plateau being raised above the edges of the riffles a distance equal to the desired depth of material above said edges, whereby the surface of the material in the main portion of the table will be in a plane coinciding with the surface of the plateau. 115

3. The combination of a transversely inclined concentrating-table, having an inclined raised portion arranged along a diag- 120 125 130

onal line relative to the line of movement of the table and in proximity to the concentrates discharge edge, and riffles arranged on the surface of said table and extending from 5 the rear end of said table and terminating in a diagonal line, said riffles being of substantially uniform height for a major portion, and in the direction of the length thereof, said riffles being provided with a beveled 10 portion extending toward one end thereof from said portion of uniform height, said beveled portion of the riffles corresponding approximately with said inclined raised portion of the table, and means for reciprocating 15 said table in the direction of the length of said riffles.

4. The combination of a transversely inclined concentrating-table having an upwardly inclined portion arranged along a 20 diagonal line relative to the line of move-

ment of the table and in proximity to the concentrates discharge edge, riffles arranged on the surface of said table and extending toward the mineral discharge edge, said riffles being provided with an abruptly beveled 25 portion extending toward one end thereof to maintain their upper edges and the surface of the deck substantially parallel in proximity to the inclined portion, said beveled portion of the riffles corresponding approximately with said upwardly inclined portion of the table, and means for reciprocating said table.

In testimony whereof I have hereunto set my hand.

EMIL DEISTER.
